United States Patent Office

Des. 209,325

Patented Nov. 21, 1967

209,325

SERVICE STATION CABINET

Homer F. King, Elmhurst, Ill., assignor to Advertising Metal Display Co., Chicago, Ill., a corporation of Illinois

Original design application Jan. 24, 1966, Ser. No. 730,
now design Patent No. 206,903, dated Feb. 7, 1967.
Divided and this application Aug. 29, 1966, Ser. No.
4,909

Term of patent 14 years

(Cl. D52—2)

FIG. 1 is a perspective view of a service station cabinet, taken from the front and one side, showing my new design;

FIG. 2 is a front elevational view thereof showing the tray in retracted position;

FIG. 3 is a perspective view of the rear thereof with the tray retracted.

The dominant features of the design reside in the portions shown in full lines.

This application is a division of design application Ser. No. D.730, filed Jan. 24, 1966, now Patent No. D.206,903 granted Feb. 7, 1967.

I claim:
The ornamental design for a service station cabinet, as shown and described.
